[57] CLAIM

The ornamental design for a chain link, as shown and described.

DESCRIPTION

FIG. 1 is a perspective view of a chain link showing my new design;

FIG. 2 is a top plan view;

FIG. 3 is a side elevational view;

FIG. 4 is a right front elevational view;

FIG. 5 is a bottom plan view;

FIG. 6 is a rear elevational view along the lines 6—6 of FIG. 3;

FIG. 7 is a perspective view of a chain link showing a second embodiment of my new design;

FIG. 8 is a top plan view of FIG. 7;

FIG. 9 is a side elevational view of FIG. 7;

FIG. 10 is a front elevational view of FIG. 7;

FIG. 11 is a bottom plan view of FIG. 7;

FIG. 12 is a rear elevational view along the lines 12—12 of FIG. 9;

FIG. 13 is a perspective view of a chain link showing a third embodiment of my new design;

FIG. 14 is a top plan view of FIG. 13;

FIG. 15 is a side elevational view of FIG. 13;

FIG. 16 is a right front elevational view of FIG. 13;

FIG. 17 is a bottom plan view of FIG. 13; and,

FIG. 18 is a rear elevational view along the lines 18—18 of FIG. 15.

*FIG. 2.**FIG. 1.*6. *FIG. 3.**FIG. 4.**FIG. 5.**FIG. 6.**FIG. 8.**FIG. 7.**12. FIG. 9.**FIG. 10.**FIG. 11.**FIG. 12.*FIG. 14.

FIG. 13.

18. FIG. 15.

FIG. 16.

FIG. 17.

FIG. 18.
